Daniel L. Morris

UNITED STATES PATENT OFFICE

OSCAR A. PEDERSEN, OF NEW YORK, N. Y.

ROOF CONSTRUCTION

Application filed March 11, 1927. Serial No. 174,497.

The present invention relates to an improved method of forming roofs and more particularly to a method of forming a building unit with a tile formation so as to adapt 5 the same for use in roofs.

Although I consider that my method may be applied to any building unit, I have in mind using it particularly with a building unit, such as disclosed in U. S. Patent 10 1,700,512, issued to me on January 29, 1929, comprising spaced slabs of building material, such as concrete, reinforced and insulated to prevent passage of moisture and cold there-through.

15 In carrying out the invention, I preferably cast the building unit on a suitable form placed on a horizontal casting table, thereby to provide tiles in the building unit shaped in correspondence with the forms and after the 20 material of the building unit has set, remove the unit from the forms. The forms accurately shape the tiles into the finished configuration desired and it is not necessary to subsequently perform any work in shaping or 25 smoothing the tiles.

In the drawings:

Figure 1 is a sectional view through a roof showing the application of the invention in practice;

30 Figure 2 is a sectional view through a building unit showing the manner in which the unit is cast on forms placed on a horizontal table, the table being indicated in side elevation; and

35 Figure 3 is an enlarged view similar to Figure 2 of casting forms adapted to be employed in my method.

Referring now to the drawings in which I have disclosed an embodiment of the invention 40 for the purpose of illustration and to the details of which I do not intend to be confined, the roof is composed of a plurality of building units, suitably connected and joined together and having on their upper surface tiles of any 45 desired form or configuration. The building unit preferably employed has an inner smooth slab, 10, of building material such as concrete and an outer tiled slab, 11, the two slabs being spaced and reinforced as by means 50 of steel I-beams, 12. In each slab I prefer-

ably incorporate reinforcement, 13, such as chicken wire, or a metal lathe, and between the slabs I preferably insert sheets of insulating material, 14, which may be of wood, cork, fibrous or any other insulating material and 55 which serves to prevent the passage of cold and moisture through the roof. As shown in the drawings, the two sides of the roof are jointed together at the peak, 15, by a waterproof joint and the lower ends of the sides are 60 tied to the top floor, 16, of the building as by means of bolts, 17, or the like, thus providing a sturdy, strong, and rigid construction.

In the process of casting the building unit I employ forms shaped to give any desired 65 type or style of tiles and lay the same on a horizontal casting table, such as indicated at 18. I then cast the building unit on top of the forms, preferably using the method disclosed in my patent mentioned above, first 70 by casting the slab, 11, on the forms then by placing the spacing means, 12, over the slab, 11, and finally by casting the slab, 10, on top of the spacing means. The particular method employed in casting the slab 10 on 75 top of the spacing means is discussed in U. S. Patent 1,700,512, issued to me on January 29, 1929. The result of this operation is that the outer slab 11 of the building unit is shaped by the forms so as to give the desired tile 80 formation. After the casting has properly dried and set, the entire casting together with the forms can be run off the table and the forms picked off, leaving the building unit with the desired tile formation and 85 ready to be incorporated in the roof of a building.

While I consider my invention is applicable for obtaining any style or shape of tiles and that it may be used in conjunction 90 with any suitable forms, for the purpose of illustration, I have shown in Figure 3 a form construction that may be employed in the practice of the process. By reference to said figure, it will be noted that the construction 95 disclosed comprises a plurality of Z shaped form members, 19, preferably of metal and interengaging one another in the manner indicated to provide tiles of shingle conformation. The entire form may be built up by 100

putting together a number of these form members on the table and thus may be obtained units of various sizes to provide building units of various sizes.

8 It is obvious that the characteristic feature of the invention is susceptible of wide variations in constructional embodiments and I desire to be limited only by the state of the prior art and the scope of the appended 10 claim.

10 I claim:

The method of forming a roof construction which comprises casting a slab of building material on a form placed in horizontal 15 position, to provide tiles of shingle conformation in the slab, shaped in correspondence with the form, placing spacing means above said slab, lining the area between said spacing means with insulating material, 20 casting another slab on said spacing means and removing the structure thereby resulting as a unit from the form after the material of the slabs has hardened.

In testimony whereof, I have signed my 25 name to this specification this 10th day of March, 1927.

OSCAR A. PEDERSEN.
